CLAIM

I claim the ornamental design for a midrail for venetian blind type coverings for architectural openings, as shown.

DESCRIPTION

FIG. 1 is an isometric view of the rail looking downwardly toward one end of the midrail for a venetian blind type covering for architectural openings.

FIG. 2 is an isometric view of the rail looking upwardly at the bottom from the same end as in FIG. 1.

FIG. 3 is a right-end elevation of the rail as shown in FIG. 1.

FIG. 4 is a rear elevation.

FIG. 5 is a bottom plan view.

FIG. 6 is a front elevation.

FIG. 7 is a top plan view; and,

FIG. 8 is a right-end elevation of the rail as viewed in FIG. 2.
